United States Patent Office.

HIRAM W. HUBBARD AND FRANCIS P. FOLLETT, OF HARTFORD, CONNECTICUT,

Design No. 3,967, dated April 12, 1870.

DESIGN FOR A HAND-STAMP.

The Schedule referred to in these Letters Patent and making part of the same.

We, HIRAM W. HUBBARD and FRANCIS P. FOLLETT, of Hartford, county of Hartford and State of Connecticut, have invented a new and original Design for a Hand-Stamp, of which the following is a specification.

The nature of our design is fully represented by the accompanying drawing, to which reference is made.

The figure is a side elevation of about the actual size of the hand-stamp as made.

The letter *a* designates the frame, made, preferably, of cast metal.

b is a vertical shaft, playing up and down in the socket *a'*.

c is the box or case for holding the types which do the marking, an end view of which only is seen, and in this end is the screw *d* for locking the types into the case.

e is a spiral spring, which keeps the shaft *b* up in place.

f is a button, upon which to strike with the palm of the hand, and thus send the types smartly down on the cloth or other article to be marked.

Claim.

We claim as our invention—

The design for a hand-stamp, as shown.

Dated March 7, 1870.

HIRAM W. HUBBARD.
FRANCIS P. FOLLETT.
